UNITED STATES PATENT OFFICE.

JOSEPH H. ORDWAY, OF BROOKLINE, MASSACHUSETTS, ASSIGNOR TO BOSTON BLACKING COMPANY, OF CAMBRIDGE, MASSACHUSETTS, A CORPORATION OF MAINE.

MACHINE FOR USE IN MANUFACTURING STIFFENERS FOR BOOTS AND SHOES.

1,312,567.

Specification of Letters Patent. Patented Aug. 12, 1919.

Application filed August 17, 1916. Serial No. 115,534.

To all whom it may concern:

Be it known that I, JOSEPH H. ORDWAY, a citizen of the United States, residing at Brookline, in the county of Norfolk and State of Massachusetts, have invented certain Improvements in Machines for Use in Manufacturing Stiffeners for Boots and Shoes, of which the following description, in connection with the accompanying drawings, 10 is a specification, like reference characters on the drawings indicating like parts in the several figures.

This invention relates to the manufacture of stiffeners for parts of the uppers of boots and shoes and is herein illustrated in connection with a machine for applying stiffening material to box toe blanks.

In the patent to Knipe No. 1,127,641 there is disclosed a box toe or shoe boxing made by saturating with melted wax all of a blank of fabric except the margin thereof, said margin being left unsaturated so as to facilitate the stitching operation and the pulling over and lasting operations in which said 25 margin is gripped by pincers. Hitherto it has been customary to apply the melted wax or other stiffening material to the fabric blank by means of a hand tool, the operative face of which corresponds in shape and size 30 to that portion of the blank which is to be saturated. This tool is dipped in the melted wax and then pressed upon the blank. Inasmuch, however, as such blanks are commonly made of thick felt-like material, such 35 as canton flannel, it becomes necessary to apply the wax to both sides in order to cause the wax to permeate the blank. The general object of the present invention is to obviate this hand operation and at the same 40 time to cause the blank to be permeated thoroughly by the stiffening material.

One feature of the invention comprises in a machine of the class described, a reservoir for stiffening material, a member against 45 which the blank may be pressed, a carrier having a material-holding depression in its upper face, and means for causing the carrier to raise material from the reservoir and apply it to the blank. With this construction a definite measured amount of material 50 is forced into each blank to impregnate it.

It is desirable that the blank be thoroughly impregnated with the stiffening material; and inasmuch as these blanks are 55 commonly quite thick, a more thorough im-

pregnation can then be obtained by applying stiffening material to both sides of the blank under pressure. Another feature of the invention comprises a pair of opposed carriers, means for supplying said carriers with stiffening material, and means for causing said carriers to press material into both sides of a blank.

These and other features of the invention including certain details of construction and combinations of parts will be described in connection with an illustrative machine and pointed out in the appended claims.

Referring now to the accompanying drawings:

Figure 1 is a perspective of a machine in which the present invention is embodied;

Fig. 2 is a detail partly in section showing in full lines the normal positions of the carriers with respect to the level of the stiffening material and in dotted lines their positions when one is applying stiffening material to the other;

Fig. 3 is a detail principally in elevation of the clutch and cams; and

Fig. 4 is a perspective of a piece of work which has been operated upon.

Mounted on a suitable frame is a reservoir 5 for the stiffening material. This material is solid at ordinary temperatures and 85 in the illustrative machine is melted and maintained in liquid form by electric heat units, not shown, which are carried in the walls of the reservoir and to which electricity is conducted through wires 7. The 90 particular means for applying heat to the reservoir is immaterial, and the specific means used will not be described further. The reservoir is divided by a partition, part of which is a screen 9, into a main compartment, into which the lumps of solid stiffening material, one of which is shown at 11, may be placed prior to being melted, and a well from which the hot liquid stiffening material is raised and applied to the blanks. 95

Projecting through the bottom of the reservoir is a rod 13 having fastened to its upper end a carrier 15. This carrier (see Fig. 2) is adjustably held in place by a screw bolt 17 threaded through said carrier and contacting with said rod. Normally this carrier is located beneath the level of the stiffening material; and its upper operative face is concave to provide a pocket or depression which is designed to hold a small amount of 100 105 110

stiffening material when the carrier is forced up out of the liquid. Located above the liquid stiffening material and opposed to the lower carrier 15 is an upper carrier 19 adjustably fastened by a set screw 21 to a rod 23, said carrier having stretched over its operative face a piece of fabric 25 held in place by a band 27. A heat unit of suitable form to which electricity may be led by wires 29 10 keeps this carrier at a proper temperature.

Located between the pair of carriers and in their paths of movement is a hollow support 31, the outside dimensions of which are less than those of the upper carrier 19 while 15 the inside dimensions at the extreme top are slightly greater than those of the lower carrier 15. The opening through the support 31 is tapering, and a guide 33 is fastened to the lower edge to assist in guiding 20 the surplus liquid back into the reservoir. In the illustrative machine, which is designed to operate upon box toe blanks, the outline of the face of the lower carrier is similar to but somewhat smaller than the 25 outline of the blank so that the stiffening material will be applied to the under side of the middle portion of the blank as indicated at 35 in Fig. 4, leaving the margin 37 in its original state. The upper carrier has 30 the same general outline as the lower carrier but is slightly larger so as to contact with the rim of the hollow support 31.

Assuming that the parts of the machine thus far described are in the positions shown 35 in full lines in Fig. 2 and that the upper carrier has been loaded with stiffening material, a box toe blank is placed upon the hollow support 31 with its margin, which is not to be saturated, projecting beyond 40 the edge or rim of said support. The two carriers are then moved into approximately the positions shown in dotted lines, the upper carrier reaching its position first and clamping the blank firmly in place, and the lower 45 carrier reaching its operative position a moment later. The middle portion of the blank is thus gripped firmly, and the stiffening material forced thoroughly into the interstices of the fabric. The carriers then return to the full line positions to permit the 50 operator to remove the blank and to prepare for the application of another load of stiffening material to the upper carrier. The cycle of movements, which has been described 55 above, is then repeated but with no blank in place, the lower carrier supplying stiffening material to the upper carrier as shown in dotted lines in Fig. 2; and the parts come to rest in the full line positions 60 preparatory to operating upon a second blank.

Referring now more particularly to Figs. 1 and 3, the mechanism by which the carriers are operated will be described.

65 The square rod 23, to which the upper car-

rier is fast, slides in a bearing in a stationary bar or bracket 39. A rocker arm 41 angularly movable about a stationary rod 43 is attached at its forward end by a link 45 to the rod 23 and at its rear end is pivoted to an upright rod 47. The lower end of this rod 47 passes through a slot in a cam lever 49 and is held in place with respect to this lever by a collar 51, a second collar 53 and a coiled spring 55 located between the collar 53 and the cam lever 49, the purpose of this yielding connection being to impart yielding downward movement to the upper carrier 19. The cam lever 49 swings about a rod 57 and is held in contact with a cam 59 by a spring 61 fast at one end to said lever and at the other to the floor or other stationary element. The cam 59 as well as the cam 63 which, as will presently be explained, actuates the lower cam is loose on the driving shaft 65. These two cams are rigid with each other as well as with a gear 67 and a clutch member 69. A second clutch member 71 slidably keyed to the shaft 65 is provided with a groove to receive a pin 73 on a lever 75, the hub of which is fast to a rod 77 loosely mounted in bearings in the frame of the machine. Near the outer end of this rod is fastened an arm 79 which is connected as shown to a treadle 81. Power having been applied to the driving shaft 65 through a pulley 83 depression of the treadle will throw the clutch members 69, 71 into engagement. This will cause rotation of the cam 59 and reciprocation of the upper carrier 19. As has been explained above, it is desirable that the carrier be given two complete reciprocations and then brought to rest. To accomplish this a gear 85 having twice the number of teeth of the gear 61 meshes with said gear 61 and is provided with a projecting portion 87 which acts against a small roll on the arm 75 to throw out the clutch after two revolutions of the shaft 65. The lower carrier rod 13 is yieldingly connected with a cam lever 89 by means similar to that connecting the rod 47 with the cam lever 49 comprising a collar 91, a coiled spring 93 and a second collar on the lower end of the rod. The cam lever 89 swings about a stationary rod 95 and is held in contact with the cam 63 by a spring 97.

The illustrative machine is equipped with two pairs of carriers and with two box toe supports, the members of one set being larger than those of the other for the reason that two sets are usually sufficient to take care of all the sizes in a case of shoes, the smaller support and carriers being used, for example, for all sizes below number 7 and the larger support and carriers for all sizes above number 7. It is desirable, however, to provide supports and carriers of different sizes on men's work from those used on 130

ladies' or children's, and to provide supports and carriers of different shape than those shown for use with counters or other stiffeners. In order to provide for these and 5 similar conditions, the supports are interchangeable and are so constructed and attached to the frame that when in place they are centered with respect to paths of movement of the carriers. Each support has 10 fast to it three bars 98, one of which rests upon the partition while the other two rest upon a wall of the receptacle and are fastened to it by screws. The length of these 15 bars is such and the screw holes so located that, as has been stated above, each support, irrespective of its size or shape, is centered with respect to the paths of movement of the carriers. It will be understood that a set of several interchangeable supports 20 are provided with each machine.

Inasmuch as the two supports and the two sets of carriers and their operating mechanisms are substantially alike, only one has been described in detail. To the other support, carriers, etc., reference numerals increased by one hundred have been applied in order to identify the corresponding parts.

In the operation of the machine the operator depresses the treadle 81 whereupon the 30 shaft 65 makes two revolutions thereby causing the carriers to contact twice. In this way the upper carrier is given a preliminary load of stiffening material. The machine is now ready for use. The box toe blank may 35 be operated upon either before or after it has been incorporated in the upper of a shoe. In the latter case the operator first draws back the leather tip, the lining and the reinforcing pieces as shown in Fig. 4. 40 In either case the box toe blank is placed on the hollow support with its margin projecting beyond the rim of said support, and the treadle is depressed. The carriers first grip the box toe blank to impregnate it with 45 stiffening material as has been described. After they have separated, the blank is removed. The carriers then come together so as to load the upper carrier, and finally come to rest in the position shown. Mean- 50 time the operator has picked up a new blank and is ready to present it on the support and depress the treadle again.

Although the invention has been described in connection with a particular machine, it 55 should be understood that the invention is not limited in the scope of its application to the particular machine which has been shown and described.

Having thus described my invention, what 60 I claim as new and desire to secure by Letters Patent of the United States is:

1. A machine of the class described, having in combination, a reservoir for stiffening material, a pair of carriers and means 65 including the reservoir for supplying said

carriers with stiffening material and for causing said carriers to apply material to both sides of a blank.

2. A machine of the class described, having in combination, a pair of carriers, means 70 for supplying said carriers with stiffening material, and means for causing said carriers to apply material to both sides of a blank.

3. A machine of the class described, having in combination, a pair of carriers, a 75 reservoir for stiffening material, and means for causing said carriers to apply material from said reservoir to both sides of a blank.

4. A machine of the class described, having in combination, a reservoir for stiffening 80 material, a support for a blank, said support being constructed to expose the middle portion of the blank, a pair of carriers and means for causing the carriers to grip said middle portion. 85

5. A machine of the class described, having in combination, a reservoir for stiffening material, a pair of opposed carriers, means including the reservoir for supplying said carriers with stiffening material, 90 and means for causing said carriers to apply material to both sides of a blank.

6. A machine of the class described, having in combination, a reservoir for stiffening material, a pair of opposed carriers, springs 95 through which said carriers are operated, means including the reservoir for supplying said carriers with stiffening material, and means for causing said carriers to apply material yieldingly to both sides of a blank. 100

7. A machine of the class described, having in combination, a reservoir for stiffening material, a pair of opposed carriers adapted to hold such material, a support for a blank located in the paths of movement of the carriers, and means for causing the carriers to grip the blank between them. 105

8. A machine of the class described, having in combination, a reservoir for stiffening material, a pair of opposed carriers 110 adapted to hold such material, springs through which said carriers are operated, a support for a blank located in the paths of movement of the carriers, and means for causing the carriers to grip the blank yieldingly between them. 115

9. A machine of the class described, having in combination, a reservoir for stiffening material, a pair of opposed carriers normally located respectively in the stiffening material and above it, a support for a blank located above the material and in the path of movement of the carriers, and means for causing the carriers to grip the blank between them. 120

10. A machine of the class described, having in combination, a reservoir for stiffening material, a pair of opposed carriers normally located respectively in the stiffening material and above it, springs through which 130

- said carriers are operated, a support for a blank located above the material and in the path of movement of the carriers, and means for causing the carriers to grip the blank yieldingly between them.
11. A machine of the class described, having in combination, a reservoir for stiffening material, a pair of opposed carriers movable toward and from each other, means including the reservoir for supplying said carriers with stiffening material, a support for a blank, said support being hollow to permit one of said carriers to move through it, and means for causing said carriers to apply material to both sides of a blank placed on said support.
12. A machine of the class described, having in combination, a reservoir for stiffening material, a pair of opposed carriers movable toward and from each other, springs through which said carriers are operated, means including the reservoir for supplying said carriers with stiffening material, a support for a blank, said support being hollow to permit one of said carriers to move through it, and means for causing said carriers to apply material yieldingly to both sides of a blank placed on said support.
13. A machine of the class described, having in combination, a reservoir for stiffening material, opposed carriers adapted to hold a supply of said material, springs through which said carriers are operated, a hollow support for a blank located between said carriers, means for causing one carrier to hold the blank upon the support, and means for causing the other carrier to raise stiffening material from said reservoir and apply it yieldingly to the blank so held.
14. A machine of the class described, having in combination, a reservoir for stiffening material opposed carriers adapted to hold a supply of said material, a hollow support for a blank located between said carriers, means for causing one carrier to hold the blank upon the support and means for causing the other carrier to raise stiffening material from said reservoir and apply it to the blank so held.
15. A machine of the class described, having in combination, a reservoir for stiffening material, opposed carriers normally located respectively in said stiffening material and above it, a hollow support for a blank located between said carriers, means for causing the upper carrier to descend upon the blank and hold it against the support, and means for causing the lower carrier to rise and apply material to the under side of the blank so held.
16. A machine of the class described, having in combination, a reservoir for stiffening material, opposed carriers normally located respectively in said stiffening material and above it, a hollow support for a blank located between said carriers, springs through which said carriers are operated, means for causing the upper carrier to descend upon the blank and hold it against the support, and means for causing the lower carrier to rise and apply material yieldingly to the under side of the blank so held.
17. A machine of the class described, having in combination, a reservoir for stiffening material, carriers for said material, means for loading one carrier from the other, and means for causing the loaded carriers to grip a blank placed between them.
18. A machine of the class described, having in combination, a reservoir for stiffening material, opposed carriers adapted to hold such material, means for causing said carriers to grip a blank placed between them, and means for causing one carrier to apply stiffening material to the other preparatory to gripping the blank.
19. A machine of the class described, having in combination, a reservoir for stiffening material, opposed carriers normally located respectively in said material and above it, means for causing said carriers to grip a blank between them, and means for causing one carrier to apply stiffening material to the other preparatory to gripping a subsequently presented blank.
20. A machine of the class described, having in combination, a reservoir for stiffening material, a pair of opposed carriers adapted to hold such material, said carriers being capable of movement first to cause one carrier to raise stiffening material from said reservoir and apply it to the other carrier and then to return the carriers to their normal positions of rest, and treadle controlled means for imparting two such movements to the carriers and then bringing them to rest.
21. A machine of the class described, having in combination, a reservoir for stiffening material, a pair of opposed carriers adapted to hold such material, said carriers being capable of movement first to cause one carrier to raise stiffening material from said reservoir and apply it to the other carrier and then to return the carriers to their normal positions of rest, and means for imparting two such movements to the carriers and then bringing them to rest.
22. A machine of the class described, having in combination, a reservoir for stiffening material, a pair of opposed carriers normally located one in the material and one above it, said carriers being capable of reciprocation first to bring them into contact and then to return them to normal position, and means for imparting two reciprocations to the carriers and then bringing them to rest in their normal positions.

23. A machine of the class described, having in combination, a reservoir for stiffening material, a pair of opposed carriers normally located one in the material and one above it, said carriers being capable of reciprocation first to bring them into contact and then to return them to normal position, and treadle controlled means for imparting two reciprocations to the carriers and then bringing them to rest in their normal positions.

24. A machine of the class described, having in combination, a reservoir for stiffening material, a support for a blank located above said material, a carrier having a material holding depression in its upper face, and means for causing said carrier to raise material from said reservoir and apply it to a blank.

25. A machine of the class described, having in combination, a reservoir for stiffening material, a support for a blank located above said material, a carrier having a material holding depression in its upper face, and treadle controlled means for causing said carrier to raise material from said reservoir and apply it to a blank.

26. A machine for applying stiffening material to a box toe blank having a member against which the blank may be pressed, a reservoir for the stiffening material, a carrier normally submerged in the material, the operative face of the carrier having a pocket therein the outline of which is similar to that of the blank but of smaller dimensions, and means for raising the carrier out of the material and pressing it against the blank with the center of the material carrying

pocket in the carrier against the approximate center of the blank.

27. A machine for applying stiffening material to a box-toe blank having, in combination, a member having a yielding face against which the blank may be pressed, a reservoir for the stiffening material, a carrier normally submerged in the material the operative face of the carrier having an outline similar to that of the blank but of smaller dimensions, and means for raising the carrier out of the material and pressing it against the blank with the center of the material-carrying face of the carrier against the approximate center of one face of the blank.

28. A machine for applying liquid stiffening material to an absorbent box-toe blank having, in combination, a member against which the blank may be pressed, a reservoir for the stiffening material, and treadle-controlled means for taking a measured quantity of material from the reservoir and forcing it into the blank.

29. A machine of the class described, having, in combination, a reservoir for stiffening material, a member against which a blank may be pressed, said member being located above the level of the stiffening material, a carrier having a material-holding pocket at its upper portion, and means for causing the carrier to raise material from the reservoir and to press it against the blank.

In testimony whereof I have signed my name to this specification.

JOSEPH H. ORDWAY.
